COLLAPSIBLE TOOTHBRUSH

Sadie Stuckey, Tulsa, Okla.

Application March 27, 1952, Serial No. 278,775

1 Claim. (Cl. 15—185)

1

This invention relates to toothbrushes and has for its primary object the provision of a case of the collapsible-type which, when not collapsed or in an extended condition, exposes the bristles of the toothbrush itself for normal use, and also serves as an extension for the handle of the brush.

It is the most important object of this invention to provide a combined case and handle extension for toothbrushes that includes a pair of substantially identical elements, each pivotally secured to the handle of the brush in a manner to cooperate in completely enclosing the brush, including its handle and its bristles when the two pivotally mounted elements are at one end of their paths of travel and cooperable in presenting an extension for the handle of the brush when the elements are swung to the opposite end of their paths of travel.

Another important object of this invention is to provide structure of the aforementioned type, embodying a pair of U-shaped elements, the legs whereof both receive the handle of the toothbrush therebetween for swinging movement relative to the handle, one of the elements receiving the other element when the same are operating as a case and being received by the other element when the structure is conditioned for use as an extended handle for the toothbrush.

Other objects embodying details of construction, include the way in which the two U-shaped elements are pivotally mounted to the brush handle for swinging movement on different axes; the way in which a third U-shaped member in the nature of a spacer is provided on the handle for pivotally receiving the primary U-shaped elements; the way in which the pivoting means operates to hold the handle against displacement with respect to the spacer; and many more minor objects, all of which will be made clear as the following specification progresses, reference being had to the accompanying drawing, wherein:

Figure 1 is a top plan view of a collapsible toothbrush made according to the present invention showing the same collapsed.

Fig. 2 is a cross-sectional view taken on line II—II of Fig. 1.

Fig. 3 is a side elevational view showing one of the elements swung to an extended position with respect to the handle of the toothbrush and the other swingable element still in embracing relationship to the toothbrush.

Fig. 4 is a top plan view with the swingable elements in the position shown in Fig. 3.

Fig. 5 is a perspective view showing the toothbrush ready for use; and

2

Fig. 6 is a transverse, cross-sectional view taken on line VI—VI of Fig. 3.

An ordinary toothbrush is illustrated in the drawing and broadly designated by the numeral 10, it being understood that the precise shape, form and nature of the toothbrush 10 is of no particular consequence to the invention as such.

Brush 10 has a handle 12 having a plurality of bristles 14 in the usual manner. In the embodiment chosen for illustration, the handle 12 is appreciably shorter than is normal in devices of this character, but here again, the length of the handle 12 may be varied to suit the desires of the manufacturer.

15 In accordance with this invention, there is provided a pair of substantially identical U-shaped elements 16 and 18, a U-shaped member 20 and pivot pins 22 and 24 for elements 16 and 18 respectively. The U-shaped member 20 is in the nature of a spacer and provided with a pair of legs or fingers 26 and 28 that embrace the handle 12 at that end thereof opposed to bristles 14. Eight 30 of the member 20 bears against the proximal free end of the handle 12.

20 25 The pin 24 traverses the spacer member 20 and is fitted within a semi-circular, transverse groove 32 in the leg 28, as well as a similarly shaped groove 34 in the normally lowermost face of handle 12 as shown in Fig. 2. The pivot pin 22 is disposed in a plane substantially perpendicular to the plane of pin 24 and slightly offset relative thereto. The pin 22 also traverses the spacer member 20 through the bight 30 and rests within a semi-circular groove 36 formed in the end 30 35 of handle 12. It is thus seen that the pins 22 and 24 aid in interlocking the handle 12 and the spacer 20, but additional means for connecting spacer 20 to the handle 12 may be provided if desired.

40 45 U-shaped element 16 is provided with a pair of identical parallel legs 38 and 40 and a bight 42. Likewise the element 18 is U-shaped and has a pair of identical parallel legs 44 and 46, as well as a bight 48. The legs 38 and 40 embrace the spacer 20 and lie flatly against the outer faces of the legs 26 and 28 thereof. It is seen that the pivot pin 22 swingably mounts the element 16 to the spacer 20 and therefore, to the toothbrush 10, pin 22 passing through legs 38 and 40 adjacent the free ends thereof. The element 18 likewise embraces the spacer 20 but lies flatly against the sides of the handle 12, the legs 26 and 28 and the bight 30. Pivot pin 24 passes through the legs 44 and 46 adjacent the free end thereof opposite to bight 42 to swingably mount the U-shaped element 18 to the spacer

20 and accordingly, to the handle 12 of the toothbrush 10.

The distance between the legs 38 and 40 of the element 16 is substantially the same as the width of the legs 44 and 46. By the same token, the distance between the legs 44 and 46 is substantially the same as the width of the legs 38 and 40. The length of the legs 38 and 40 may be substantially the same as the length of the legs 44 and 46. Or the distance between the pin 24 and the bight 48 may be substantially the same as the distance between pin 22 and bight 42. By offsetting the pins 22 and 24, it is possible for element 16 to receive the element 18 when the toothbrush is extended ready for use as shown in Fig. 5 and conversely, the element 18 may receive the element 16 when the toothbrush is collapsed as shown in Figs. 1 and 2 of the drawing.

Assuming the toothbrush to be collapsed as shown in Figs. 1 and 2 of the drawing, it is seen that the handle 12 and the bristles 14 are embraced by the element 16. The leg 38 of element 16 overlies the normally uppermost face of handle 12, whereas the leg 40 of element 16 is disposed beneath the bristles 14 as shown in Fig. 2. The bight 42 of the element 16 is disposed across that end of handle 12 proximal to bristles 14. In this connection it is to be noted that the bights 42 and 48 have their longitudinal axes substantially parallel with their corresponding pins 22 and 24 respectively. Not only element 16, but the element 18, embraces the toothbrush 10 in the condition shown in Figs. 1 and 2 of the drawing, presenting a case therefor.

The leg 44 of element 16 extends along one side of the toothbrush 10, whereas the element 46 extends along the opposite side thereof, and the bight 48 is exteriorly of the bight 42. To extend the elements 16 and 18 as shown in Fig. 5 of the drawing, the operator must first swing the element 18 with respect to element 16 and brush 10 on the pivot pin 24 where element 18 extends outwardly beyond the handle 12 as shown in Figs. 3 and 4 of the drawing. Thereupon, and only after element 18 is thus fully extended, the operator swings element 16 from its position embracing the brush 10 on pivot pin 24. Such swinging movement of element 16 positions the same in embracing relationship to the bight 48 of element 18 as shown in Fig. 5.

The assembly may thereupon be placed in use by grasping the elements 16 and 18 and using the same as a toothbrush handle. These two U-shaped elements serve therefore, as an extension for the handle 12 of brush 10 and cannot swing on their pivot points 22 and 24 as long as within the grasp of the hand of the user.

Any suitable material either transparent, opaque or translucent, may be utilized, and it is clear that by the use of suitable synthetic plastics, many differing and attractive colors can be employed while presenting a sturdy, yet lightweight, over-all unit. The cooperating elements 16 and 18 completely embrace or enclose the brush

10 when in the condition shown in Figs. 1 and 2 of the drawing protecting the bristles 14 against damage and keeping the same in a clean condition. A tight fit is neither necessary nor desired and therefore, sufficient space is presented between the elements 16 and 18 when in the case-forming condition to assure drying of the bristles 14 while the unit is not in use. A rather tight swinging fit is to be preferred however, so that the legs of the two elements 16 and 18 frictionally engage the spacer 20 whereby the elements will remain in either of the two positions until the operator with slight force, imparts swinging movement thereto.

It is manifest that many modifications and changes may be made within the spirit of this invention, and it is therefore, desired to be limited only by the scope of the appended claim.

Having thus described the invention what is claimed as new and desired to be secured by Letters Patent is:

In combination with a toothbrush provided with a handle having bristles on one end thereof; a U-shaped spacer in embracing relationship to the handle at the opposite end thereof; a pair of pivot pins interconnecting the spacer and the handle, extending through the spacer; and a combined, collapsible handle extension and toothbrush case comprising a pair of U-shaped elements, each having a bight provided with a pair of laterally-extending, parallel legs, the legs of each element embracing the spacer at the free ends of the legs remote from the respective bights, one of the elements embracing the other element when the elements are disposed as an extension for the handle, said one element being mounted on one of said pivot pins for swinging movement to and from a position embracing said handle and said bristles, the other element being mounted on the other of said pivot pins for swinging movement to and from a position embracing the handle, the bristles and said one element when the latter is in said position embracing the handle and the bristles, said handle being provided with semi-circular grooves receiving and partially embracing each pivot pin respectively within the spacer for holding the toothbrush against lateral displacement relative to the spacer and for reinforcing the mounting of the pins in the spacer, said pins being so disposed that the U-shaped members swing in substantially perpendicular planes.
